AIR PUMP ADAPTER FOR INTERNAL-COMBUSTION ENGINES

Patrick J. Sheehan, Bellwood, Ill., assignor to
Super Manufacturing Corp., Chicago, Ill., a corporation of Illinois

Application June 2, 1950, Serial No. 165,737

3 Claims. (Cl. 251—122)

1

This invention is directed to new and useful improvements in air pump adapter for internal combustion engine whereby an air pump is formed, which can be used for inflating pneumatic tires. More specifically this invention is directed to a device which is adapted to be substituted for a spark plug of an internal combustion motor so that when the motor is operated, the piston of the cylinder in which the device has been substituted for the spark plug will draw outside air through the device on the downstroke and eject air under pressure on the upstroke through a conduit or hose.

It is realized that many devices have heretofore been used for the same purpose but it is the primary object of this invention to provide such a device which is superior to those because of its simplicity in design and function.

A further object of this invention is to provide a novel flap valve assembly in such a device adapted for easy construction and assembly.

Still a further object of this invention is to provide in such a device a novel flap valve assembly of parts so simple in construction that an unskilled operator can readily fabricate duplicate parts should repair or replacement be necessary in the field.

Further objects and advantages will be apparent from the following detailed specification.

In the drawings:

Fig. 1 is a side elevation view partly in section of a device embodying these inventions in operative position in the cylinder of an internal combustion engine.

Fig. 2 is an enlarged central vertical cross sectional view of the device shown in Fig. 1.

Fig. 3 is a cross sectional view taken on line 3—3 of Fig. 2.

Fig. 4 is a perspective view of the valve flap retainer.

Fig. 5 is a perspective view of the valve flap before assembly.

In detail 1 indicates a cylinder of an internal combustion engine with the adapter device 2 embodying these inventions positioned in the spark plug opening 3. A flexible air hose 4 leads from the device 2 for delivering air pressure where desired.

The adapter 2 comprises a cylindrical chamber 5 extending from the lower end to a point about midway between the two ends. An air passage 6 leads from the upper end of chamber 5 to the outlet 7. Positioned in air passage 6 is a ball valve assembly of well known construction comprising a ball 8, a lower ball seat 9, an upper seat

2

10 and air slots 11, normally closing air passage 6 but adapted to permit the escape of air under pressure.

For ease in assembly the chamber 5 is formed by a central casing 12 and a lower cap 13 secured together in threaded relation. The lower end of cap 13 has external threads 14 of the same size as the internal threads of the cylinder 1. Opposite sides of central casing 12 are provided with air intake slots 15 and opposed solid portions 16 lie between the areas of the slots 15.

The flap valve assembly for controlling the intake of air through slots 15 comprises a single rectangular piece of resilient material such as rubber forming the flap valve 17 rolled into a tubular form and inserted in the upper part of chamber 5 in casing 12 adjacent the slots 15. The length of the flap valve is less than the circumference of the upper part of chamber 5 so that the ends of the flap valve 17 when positioned in chamber 5 are spaced from each other to form a vertical trough 18.

The other part of the flap valve assembly comprises a relatively thin rectangular retainer or wedge 19 of a length substantially that of the part of chamber 5 within casing 12. The width of retainer 19 is slightly less than the diameter of the upper part of chamber 12. The corner of the upper end of retainer 19 may be curved 30 slightly for ease in assembly, as shown at 20.

The outlet 7 is in a removable threaded cap 21. It is apparent that ball 8 is placed in the device when cap 21 is removed and the ball valve assembly completed when cap 21 is screwed into position.

The flap valve assembly is placed in position when lower cap 13 has been unscrewed from main casing 12. Flap valve 17 is rolled into tubular shape and inserted into chamber 5 of casing 12 with the two spaced ends positioned between the opposed areas of the slots 15. Retainer 19 is then forced into the center of chamber 5 with one side edge bearing against the middle of flap valve 17, as shown at 22, the opposite edge positioned in the trough 18 between the two spaced ends of the flap valve 17, and bearing against the wall of chamber 5 to form a central web within the chamber 5, as clearly shown in Fig. 3. This is a forced friction fit and the middle of flap valve 17 is pinched against the wall of chamber 5 and the spaced ends are free. The curved ends 20 of retainer 19 facilitate the positioning of the retainer 19.

In operation, the usual spark plug is removed 55 from the cylinder 1 and the adapter 2 is substi-

tuted therefor. The engine is operated by the other cylinders and on the downstroke of the piston of cylinder 1 air is drawn through slots 15 into the cylinder. The free ends of flap valve 17 move inwardly to permit this intake of external air. During the downstroke of the piston the ball 8 rests in seat 9 to close outlet 7. On the upstroke the air which has been drawn into the cylinder 1 is forced upwardly to unseat ball 8 and be forced from outlet 7. During the upstroke the slots 15 are closed by flap valve 17, the pressure of the air moving upwardly from the cylinder 1 forcing the valve material against the slots 15 to close them. The air thus pumped is directed from hose 4 where desired and when finished the adapter 2 is removed and the spark plug replaced so that the engine will operate on all cylinders.

It is apparent from the above detailed specification that novelty and invention of this device rests in the extreme simplicity of the parts forming the flap valve assembly which permits utmost ease in assembly, maintenance and repair yet gives efficient results. Inasmuch as devices of this kind are used mostly in remote countries and locations where service and repair facilities are meager or entirely lacking, the desirability of such a simple assembly comprising a minimum number of uncompleted parts is easily appreciated.

I claim:

1. In an air pump adapter comprising a casing having a central cylindrical chamber with side air inlets and an air outlet, the invention that comprises an air flap assembly comprising a flap valve formed of one rectangular piece of flexible material having uninterrupted parallel edges of a length less than the circumference of the chamber said material being coiled to form a tubular lining for said chamber with spaced ends and a thin blade-like rectangular retainer having a width slightly less than the diameter of the chamber positioned centrally thereof in a forced fit one edge thereof pinching the central part of the flap valve against one side of the chamber along its full length and the other edge bearing along its full length against the opposite wall of the chamber between the spaced ends.

2. In an air pump adapter comprising a casing having a central cylindrical chamber with side

air inlets and an air outlet, the invention that comprises an air flap assembly comprising a flap valve formed of one rectangular piece of flexible material with uninterrupted parallel edges of a length less than the circumference of the chamber said material being coiled to form a tubular lining for said chamber with spaced ends and a thin flat rectangular retainer having a width slightly less than the diameter of the chamber but greater than the inner diameter of the flap valve lining, said retainer positioned vertically and centrally within the chamber in a friction fit along the full lengths of its opposed edges between the flap valve material at one side of the chamber and the inner wall of the opposite side of the chamber between the spaced ends.

3. In an air pump adapter comprising a casing having a central cylindrical chamber with side air inlets and an air outlet, the invention that comprises an air flap assembly comprising a flap valve formed of one substantially rectangular piece of flexible material of a length less than the circumference of the chamber, said material being coiled to form a tubular lining for said chamber with spaced ends, and a thin, flat, substantially rectangular retainer having a width slightly less than the diameter of the chamber but greater than the inner diameter of the flap valve lining, said retainer positioned vertically and centrally within the chamber in a friction fit between the flap valve material at one side of the chamber and the inner wall of the opposite side of the chamber between the spaced ends, one edge of the retainer bearing against the flap valve material from the top to the bottom of said material the opposite edge bearing against the inner wall the entire length of said opposite edge.
